UNITED STATES PATENT OFFICE.

GEORGE A. SINGERLY, OF PHILADELPHIA, PENNSYLVANIA.

DESIGN FOR A HORSESHOE.

SPECIFICATION forming part of Design No. 26,834, dated March 30, 1897.

Application filed February 10, 1897. Serial No. 622,866. Term of patent 14 years.

To all whom it may concern:

Be it known that I, GEORGE A. SINGERLY, a citizen of the United States, residing in the city and county of Philadelphia, State of Pennsylvania, have invented and produced a new and original Design for a Horseshoe, of which the following is a specification, reference being had to the accompanying drawings, forming part thereof.

The leading feature of my design for a horse or animal shoe is parallel grooves in the tread thereof, the same converging.

Figure 1 represents a perspective view of a

horseshoe embodying my design. Fig. 2 represents a section thereof on line *x-x*, Fig. 1. 15

In the drawings, A designates a horseshoe in the tread of which are the parallel grooves B, whose walls C converge or flare upwardly.

What I claim is—

The design for a horseshoe, substantially 20 as described and shown.

GEORGE A. SINGERLY.
